CABINET DOOR STRUCTURE

Floyd R. Eek, Des Plaines, and Worthy L. Chambers, Chicago, Ill., assignors to Motor Products Corporation, Detroit, Mich., a corporation of New York

Application July 16, 1951, Serial No. 237,018

14 Claims. (Cl. 20--35)

1

This invention relates to an improved door structure for refrigerator cabinets.

It is one of the objects of this invention to provide a door structure composed of a relatively few simple parts capable of being inexpensively manufactured and readily assembled.

It is another object of this invention to effectively reinforce the door structure by corner brackets in the form of substantially L-shaped plates, and to provide a hinge mounting for the door including hinge parts respectively secured to the legs of the corner brackets extending along one side edge of the door.

It is still another object of this invention to provide a door structure of the above general type wherein the corner brackets at one side of the door are interchangeable with the corresponding corner brackets at the opposite side edge of the door. Thus inventory is materially reduced and assembly is greatly expedited.

It is a further object of this invention to provide a door structure wherein each of the legs of the corner brackets is embossed to provide a recess of sufficient dimension to receive the part of the hinge attached to the door.

A still further object of this invention is to extend the hinge parts between the marginal edge portion of the inner panel at one side of the door and the adjacent leg portions of the brackets, and to secure the hinge parts and adjacent marginal edge portions of the inner panel to said leg portions of the brackets.

Still another object of this invention is to provide a door structure wherein the inner panel terminates short of the bottom edge of the outer panel and wherein the resulting gap is closed by a filler strip having the opposite side edge portions respectively secured to the bottom of the outer panel and to the adjacent corner brackets.

The foregoing as well as other objects will be made more apparent as this description proceeds, especially when considered in connection with the accompanying drawings, wherein:

Figure 1 is an elevational view partly broken away of the inner side of a refrigerator cabinet door structure embodying the features of this invention;

Figures 2 to 9 inclusive are respectively sectional views taken on the lines 2-2, 3-3, 4-4, 5-5, 6-6, 7-7, 8-8 and 9-9 of Figure 1;

Figure 10 is a perspective view of one of the corner brackets employed at the top of the door; and

Figure 11 is a perspective view of one of the

2

corner brackets employed at the bottom of the door.

The refrigerator cabinet door selected herein for the purpose of illustration comprises an outer panel 10, an inner panel 11 spaced laterally from the outer panel and heat insulating material 12 filling the space between the panels. The outer panel is preferably formed of sheet metal, and is transversely curved in a forward direction, as clearly shown in Figure 2 of the drawings. The marginal portions of the outer panel 10 are turned laterally inwardly to provide a reinforcing flange 13 which extends continuously around the perimeter of the outer panel and is bent forwardly at the inner edge to provide a stiffening flange 14.

The inner panel 11 of the door is preferably formed of a plurality of laminations of a plastic heat insulating material, and the central portion is bowed in a direction toward the outer panel 10. In addition the inner panel 11 is formed with a marginal portion 15 which extends continuously around the perimeter of the inner panel in substantial parallel relationship to the reinforcing flange 13. The bottom edge of the inner panel 11 terminates short of the corresponding edge of the outer panel 10, and the resulting space is closed by a filler strip 16 which is preferably formed of sheet metal. The filler strip 16 extends completely across the bottom of the door and serves to reinforce the door structure. As shown in Figures 7 and 8 of the drawings, the bottom edge of the filler strip 16 is welded or otherwise secured to the reinforcing flange 13 at the bottom of the outer panel 10, and the top edge portion of the filler strip 16 is secured to the bottom marginal edge portion 15 of the inner panel 11 by fastener elements 17. The central portion 18 of the strip 16 is bowed toward the outer panel 10, and the top edge is turned laterally inwardly to provide a flange 19, which coacts with the bowed portion 18 in reinforcing the filler strip 16.

The top and side marginal portions 15 of the inner panel are secured to the adjacent portions of the reinforcing flange 13 on the outer panel by fastener elements 20, and are insulated from the reinforcing flange 13 by a rubber gasket 21. The gasket 21 extends completely around the perimeter of the inner panel 11 and has a flange 22 at the top and sides thereof. The flange 22 extends between the reinforcing flange 13 and the adjacent marginal portions 15 of the inner panel 11. The gasket 21 also has a flange 23 at the bottom which forms a continuation of the

flange 22 and projects upwardly between the filler strip 16 and the bottom marginal edge 15 of the inner panel 11. The marginal edge portion 15 of the inner panel 11 has a recess 24 which receives an enlargement 25 on the flanges 22 and 23 of the gasket to locate the latter relative to the inner panel 11. It will also be noted that the flanges 22 and 23 are respectively secured to the reinforcing flange 13 on the outer shell 10 and to the filler strip 16 by the fastener elements 17 and 20.

The gasket 21 is further provided with a lip 26, which overlies the rear side of the marginal portions 15 on the inner door panel 11 and engages the latter inwardly beyond the fastener elements 17 and 20. The lip 26 has a hollow head portion 27, which is deformable and is positioned to engage the front wall of a refrigerator cabinet 30 around the access opening in the cabinet to provide a door seal.

In the present instance the door is hingedly connected along one side edge to the refrigerator cabinet 30 by a pair of hinges 31 having cooperating parts 32 and 33 respectively pivotally connected by vertical pins 34. The hinge parts 32 are secured to the cabinet by fasteners 35 and the hinge parts 33 are positioned at the rear sides of the reinforcing flanges 13 on the door. As shown in Figure 3 of the drawings, the reinforcing flange 13 is embossed toward the outer panel 10 of the door to provide recesses 36 for respectively receiving the hinge parts 33. The depth of the recesses 36 approximates the thickness of the hinge parts 33 so that the rear face of the hinge parts 33 lies flush with the corresponding face of the flange 13. The arrangement is such that the sealing flange 22 on the gasket 21 and the marginal edge portion 15 of the inner door panel 11 extend over the hinge parts 33.

The door structure forming the subject matter of this invention is braced at each of the four corners of the inner door panel 11 by an angle bracket 37 housed within the space between the inner and outer panels 10 and 11 respectively of the door. Each angle bracket is in the form of an L-shaped metal plate reinforced by a flange 38 extending toward the outer door panel 10 from the inner marginal edges of the leg portions 39 and 40 of the plate.

The angle brackets at the top corners of the door are identical in construction, or in other words, are interchangeable; and are indicated by the numeral 41. The leg portions 39 of the brackets 41 are welded to the front face of the portion of the reinforcing flange 13 which extends across the top of the door, and the leg portions 40 are respectively welded to the portions of the flange 13 which extend along opposite side edges of the door. The legs of the brackets 41 have openings 42 for receiving certain of the fastener elements 20, which may be in the form of self-tapping screws.

As shown in Figures 6 and 10 of the drawings, each leg of the brackets 41 has a portion embossed in a direction toward the outer door panel 10 to provide a recess 43 having openings 44 in the base portion thereof. The recesses 43 in the legs of the brackets 41 are so located and dimensioned that regardless of which of the two brackets 41 is located at the hinged edge of the door, one of the recesses 43 registers with the top hinge part 33 and receives the adjacent embossed portion of the reinforcing flange 13. The top hinge part 33 is secured to the adjacent bracket 41 by self-tapping screws 45 threaded into the openings 44. 75

The angle brackets at the bottom corners of the inner door panel 11 are also identical in construction and are interchangeable. These brackets are indicated by the numeral 46 and the horizontal leg portions 39 are welded to adjacent portions of the filler strip 16, shown in Figure 7 of the drawings. The vertical leg portions 40 are respectively welded to the portions of the reinforcing flange 13 at opposite side edges of the door. The legs of the brackets 46 also have openings therein for receiving certain of the fastener elements 17 and 20.

As shown in Figures 9 and 11 of the drawings, each leg of the brackets 46 has a portion embossed in a direction toward the outer panel 10 to provide a recess 47. The recesses 47 are so located and dimensioned that regardless of which of the two brackets 46 is located at the hinged edge of the door, one of the recesses 47 registers with the part 33 of the bottom hinge 31, and receives the adjacent embossed portion of the reinforcing flange 13. The base portions of the recesses 47 have openings therethrough and self-tapping screws 48 are employed to securely fasten the hinge part 33 to the adjacent bracket 46.

Each of the brackets 37 is preferably provided with means for locating the same in assembled relationship with the door prior to welding the brackets in place. In the present instance the above is accomplished by providing a projection 43' on each leg adjacent the free end of the latter, and by forming suitable indentations in the appropriate parts of the door structure for receiving the projections.

The four corner brackets 37 cooperate with one another to effectively brace the door structure and render it unnecessary to provide a structural frame around the perimeter of the door. Also the corner brackets 37 render it possible to hang or hinge either side edge of the door to the refrigerator cabinet structure. Moreover the brackets 41 at the top of the door are interchangeable, and the brackets 46 at the bottom of the door are also interchangeable. Thus assembly of the door is greatly expedited and production of the brackets is simplified. It is also important to note that the brackets at the hinged edge of the door provide rigid mountings for the hinge parts attached to the door, and that all of the brackets cooperate to provide a more rigid mounting for the inner door panel 11 on the outer panel 10.

What we claim as our invention is:

1. A refrigerator cabinet door structure comprising a substantially rectangular outer panel having the marginal portions extending rearwardly and turned inwardly to provide a reinforcing flange, a substantially rectangular shaped inner panel spaced laterally from the outer panel having marginal portions overlying the rear sides of the reinforcing flange and secured to said flange, means for reinforcing the corners of the door at the top of the latter, including L-shaped brackets located within the space between the panels in overlying relationship to the front side of the reinforcing flange and respectively secured to said flange at the top corners of the door, the L-shaped brackets at one side of the door being interchangeable with the L-shaped brackets at the opposite side of the door and each bracket having provision for attaching a hinge part thereto.

2. The refrigerator cabinet door structure defined in claim 1, wherein the inner panel terminates short of the bottom edge of the outer panel and wherein the resulting gap is closed by a filler

strip extending across the bottom of the door and having the opposite side edges respectively secured to the reinforcing flange at the bottom of the outer panel and to the bottom edge portion of the inner panel.

3. The refrigerator cabinet door structure defined in claim 1, wherein the outer panel is composed of sheet metal and is transversely curved in a forward direction, and wherein the inner panel is composed of a heat insulating plastic material and is bowed in a direction toward the outer panel.

4. A refrigerator cabinet door structure comprising a substantially rectangular outer panel having the marginal portions extending rearwardly and turned inwardly to provide a reinforcing flange, a substantially rectangular shaped inner panel spaced laterally from the outer panel having marginal portions overlying the rear sides of the reinforcing flange and secured to said flange, an L-shaped bracket at each top corner of the door having angularly disposed legs respectively overlying the front sides of the reinforcing flange extending along adjacent side edges of the door, and a hinge part at one vertical edge of the door extending between and secured to both the marginal portion of the inner panel and the vertical leg of the adjacent L-shaped bracket.

5. The refrigerator cabinet door structure defined in claim 4, in which heat insulating material is provided between the hinge part and adjacent marginal portion of the inner door panel.

6. The refrigerator cabinet door structure defined in claim 4, wherein the portion of the leg to which the hinge part is secured and the adjacent portion of the reinforcing flange are embossed to provide a recess for receiving the hinge part.

7. The refrigerator cabinet door structure defined in claim 6, wherein the L-shaped brackets at opposite side edge portions of the door are interchangeable.

8. The refrigerator cabinet door structure defined in claim 8, wherein the legs of each L-shaped bracket are embossed to accommodate the hinge part.

9. A refrigerator cabinet door structure comprising a substantially rectangular shaped outer panel having a marginal inturned flange, a substantially rectangular shaped inner panel spaced laterally from the outer panel and having marginal edge portions secured to the flange, substantially L-shaped brackets respectively positioned at the top corners of the door and having the legs respectively secured to the portions of the inturned flange extending along adjacent side edges of the door, additional substantially L-shaped brackets respectively positioned at the bottom corners of the inner panel and having vertically extending legs respectively secured to the inturned flange extending along opposite sides of the door, the brackets at one side edge of the door being interchangeable with the brackets at the opposite side edge of the door and each bracket having provision for attaching a hinge part thereto.

10. The refrigerator cabinet door structure defined in claim 9, wherein the outer panel extends below the bottom edge of the inner panel and wherein the resulting gap is closed by a filler

strip extending across the bottom of the door and having the opposite side edges respectively secured to the inturned flange at the bottom of the outer panel and to the adjacent legs of the bottom brackets.

11. The refrigerator cabinet door structure defined in claim 9, wherein hinge parts respectively extend between the legs of the L-shaped brackets extending along one side edge of the door and the adjacent marginal portion of the inner door panel, and wherein means is provided for securing the hinge parts to last named legs of the L-shaped brackets.

12. The refrigerator cabinet door structure defined in claim 11, wherein the inturned flange on the outer door panel has embossed portions respectively registering with the hinge parts and forming recesses within which the hinge parts are respectively seated, and wherein the L-shaped brackets have a recess in each of the legs of sufficient dimension to receive the embossed portions of said inturned flange

13. A refrigerator cabinet door structure comprising a metal outer panel, a plastic inner panel spaced laterally from the outer panel and having marginal edge portions secured to the outer panel, L-shaped reinforcing brackets respectively located between and secured to said panels at the four corners of the door, said brackets having certain of the legs extending horizontally adjacent the upper and lower horizontal edges of said door and having the other legs extending vertically adjacent the vertical edges of the door, the vertically extending legs of the brackets at one vertical edge of the door having provision for attaching hinge leaves thereto, said panels and brackets coating to provide a rigid door structure without the aid of a supporting frame.

14. A refrigerator cabinet door structure comprising a metal outer panel, a plastic inner panel spaced laterally from the outer panel and having marginal edge portions secured to the outer panel, L-shaped reinforcing brackets respectively located between and secured to said panels at the four corners of the door, said brackets having certain of the legs extending horizontally adjacent the upper and lower horizontal edges of said door and having the other legs extending vertically adjacent the vertical edges of the door, the vertically extending legs of the brackets at one vertical edge of the door having provision for attaching hinge leaves thereto, and a strip extending across the bottom of the door at the inner side thereof and having the opposite end portions respectively secured to the L-shaped brackets at the lower corners of the door, said panels, brackets and strip coating to provide the sole supporting structure for the door.
